UNITED STATES PATENT OFFICE.

BEVELY L. ADAMS AND LEN W. COOPER, OF ATHENS, GEORGIA.

BACKBAND HOOK FASTENER.

Application filed August 30, 1922. Serial No. 585,180.

To all whom it may concern:

Be it known that BEVELY L. ADAMS and LEN W. COOPER, citizens of the United States, residing at Athens, in the county 5 of Clarke and State of Georgia, have invented certain new and useful Improvements in Backband Hook Fasteners, of which the following is a specification.

This invention relates to improvements in 10 back band hook fasteners.

The primary objects of the invention are to provide a device of the character described which shall be simple in construction, significantly durable in use, cheap to 15 manufacture, and reliable.

It is well known to farmers and others that backbands, *per se*, rapidly wear out if made of material which will give a maximum of comfort to a draft animal and which 20 avoids the formation of sores and galls on the back or sides of the animal; and that it is sometimes difficult and expensive to repair devices of this class by replacing broken, worn, and essential parts. One of the 25 objects of our invention is to supply an efficient device that combines great simplicity in construction and durability in use. Our invention consists in making a backband of suitable flexible material, such as duck, 30 canvas, cotton, stuffed or filled with hair or cotton, and preferably quilted, and provided with a trace carrier which is secured to the backband by two sheets of metal, preferably made of galvanized iron, one of 35 which passes transversely around the backband near each of the ends thereof, and the other extending longitudinally of the backband over each of the said transverse sheets to a point beyond the lower or outer edge 40 thereof, and is then folded upon itself.

When these two pieces and the yielding backband are riveted together the outer end of the outer sheet is formed with an eye to receive a straight portion of a hook of 45 a trace carrier such as hereinafter described, or a hook of any other suitable construction. Each end of the backband is preferably provided with a flexible pad or wear plate of suitable material, which extends under the 50 trace carrier to protect the backband and to prolong its useful life. The metal strip which passes around the backband at each end thereof is permanently riveted or otherwise attached thereto. It is pressed into 55 the faces and edges of the backband, especially the faces, so that parts thereof will

stand out beyond the metallic plates and form a cushion that will prevent the plates, or either of them, from chafing or rubbing the sides of the draft animal.

The hook of a trace carrier as herein shown for illustrative purposes is preferably made of wire having a transverse portion, parallel with the transverse axis of the backband, which is formed into an eye of the outer metallic plate to receive such transverse portion; the sides of the hook then extend inwardly and downwardly, then outwardly, thence upwardly and thence downwardly to a point preferably in a plane 60 substantially in a line with the inner edges of the converging sides of the hook. The form of this hook and the yielding backband between the trace chain and the backband renders a keeper over the end of the hook unnecessary. As shown, one end of the hook is made a little shorter than the other end.

Referring to the drawings, in which we have shown one embodiment of our invention, and in which like numerals of reference refer to like parts,

Figure 1 is a plan view of the end of a backband embodying our invention.

Fig. 2 is a longitudinal sectional view 85 taken on the line 2—2 of Fig. 1.

Fig. 3 is a transverse sectional view taken on the line a—b of Fig. 1.

5 is the backband which is made of canvas, felt, or other suitable material, which 90 is stuffed with hair or cotton or other material and is then quilted, as shown at 6, and is provided with a wear pad or plate at its lower or outer end over which the hook extends and upon which it has its bearing. 95 This wear plate or pad can be made also of canvas, or leather, or other suitable material. 7 is a metallic plate preferably of galvanized sheet metal which passes around the band and is lapped upon itself to a 100 point beyond the further rivets. 8 is a second metallic plate, also preferably of galvanized sheet metal which is folded upon itself, forming an eye 9, and which extends back over the face of the transverse plate 105 7 and is then secured to said plate and to the backband by a series of rivets 10, preferably made of copper to prevent rusting. The plate 7 is of such length that when folded and riveted to the plate 8 and to the 110 backband 5, it will compress the face of the backband, as shown at 11, on the face

of the backband and also at the edges thereof, as at 12. This is done to prevent the plate from rubbing or chafing the sides of the draft animal wearing the same. Referring to the form of hook shown it has a straight transverse portion 13 which has its bearing in the eye 9 and has downwardly converging sides 14 which are then extended outwardly, as at 15, thence upwardly as at 16, and thence inwardly as at 17, one or both points of the ends of the hook extending inwardly to a point preferably about on a plane with the inner edges of the converging side bars.

We are aware that changes in the form and proportion of parts and materials to be used may be made without departing from the principle or sacrificing the advantages of our improvements and we therefore reserve the right to make such changes that fairly fall within the scope of our invention.

We have had very satisfactory results in

introducing our backband hook fastener into practical use. We find that it gives entire satisfaction by reason of its promotion of comfort to the draft animal, its great utility, and the cheapness in manufacturing the same.

We claim:

A backband composed of yieldable material having means for securing a hook fastener thereto, comprising a clamping plate which extends around the backband and is pressed therein so that the clamping plate is disposed beneath the surfaces of the backband thereby preventing the said plate from rubbing the sides or back of the animal, a second plate having means to receive a portion of a hook trace carrier and means for attaching the said second plate to the clamping plate.

In testimony whereof we affix our signatures.

BEVELY L. ADAMS.
LEN W. COOPER.
